United States Patent Office.

GEORGE CROWTHER, OF PHILADELPHIA, PENNSYLVANIA.

Letters Patent No. 61,723, dated February 5, 1867.

IMPROVEMENT IN SPINNING MULES.

The Schedule referred to in these Letters Patent and making part of the same.

TO ALL WHOM IT MAY CONCERN:

Be it known that I, GEORGE CROWTHER, of the city and county of Philadelphia, and State of Pennsylvania, have invented a new and useful Improvement in Spinning Mules; and I do hereby declare that the following is a full and exact description thereof, reference being had to the accompanying drawings, and to the letters of reference marked thereon.

The nature of my invention and improvement mainly consists in giving an automatic inward motion to the carriage by means of belts and pulleys combined with the rim-shaft, and winding the yarn on the bobbins or spindles at the same time; it also consists in a new construction and arrangement of the backcatch for stopping the shifter and holding it securely during the time it should remain on the loosepulley 6, on the driving-shaft C.

I am aware that there are modes of giving an automatic inward motion to the carriage, but they are of a complicated nature and liable to get out of order, while mine is simple and not easily deranged. With its use a man can operate a much larger mule than ordinarily. In the accompanying drawings—

Figure 1 represents a plan or top view of the improved mule.

Figure 2 is a front elevation of the same.

Figure 3 is a side view of ditto.

Figure 4 is a face view of the pulley 1, 1' in connection and detached from the rim-shaft.

Figure 5 is a face view of the back-catch.

Figure 6 is a side view of the lever N.

A is the standing frame, which has all the parts in connection therewith of an ordinary mule. But as these parts are well known to those skilled in the art to which my improvement appertains, I will only describe such parts as are connected with the improvement. B is the carriage, similarly constructed and arranged in relation to the standing frame A, as the carriage of an ordinary mule. C is the rim-shaft, on which I place the pulley 1, which has a flat part, 1', connected therewith by means of the sleeve D, that turns freely on the driving-shaft C. This pulley is shown detached in fig. 4. A loose pulley, 2, is placed on said sleeve before fastening the part 1 to the sleeve. The said pulley 2 has a groove for the reception of the belt G, and a flat part, a, to receive the driving belt C'; at which time the said belt also comes over the flat part 1' of pulley 1. There are pulleys, 3 and 4, on the shaft E, the former being fast on the shaft and the latter turning loosely thereon. Pulley 3 is connected with pulley 1 by means of the cross-belt F, to revolve the shaft E, and give the inward motion to the carriage, said shaft being connected with the drawing-cord e by means of the pulley 3' on the end of the shaft. The loose pulley 4 has two grooves in its face, one for the reception of the open belt G, which also connects with pulley 2, the other receives the cross-belt I, which makes a further connection with pulley 5, on the twist-shaft J, to wind the yarn on the bobbins or spindles, the intermediate parts between the shaft and the spindles being constructed and arranged in the usual manner. For holding the shifter K in place when the driving-belt C' is on the loose pulley 6, I construct the back-catch L, with the shoulder b, as seen in fig. 5. The said back-catch is jointed at its rear end to the upper end of the vertical rod M, the lower end of which is jointed to the short end of the horizontal lever N, whose fulcrum-pin c is held by lugs on the under side of the cross-bar O, to which the standard P of the shifter is secured. Near the front end of the lever N there is a lug, d, under which the adjustable rod Q, which projects from the carriage, passes in the back motion of the latter, to raise the shoulder of the back-catch above the shifter handle in the outward motion of the same. When the said rod has passed the lug the forward end of the lever N falls, which action raises the vertical rod M, and causes the front end of the back-catch to descend and catch over the handle of the shifter and hold it in place while the carriage should remain out. And when the operator has started the carriage inwards, and the rod Q, which projects therefrom, passes under the lug or projection d, of the lever N, and raises the front end of the lever, the rear end thereof in its downward motion, by causing the rod M to descend, operates the back-catch L, and disengages the shoulder b from the shifter, and the latter is then instantaneously operated by the spring R, acting through its usual connection; and the driving-belt C' is brought over the flat faces 1' and a, of the pulleys 1 and 2, which, acting through the belts and pulleys above-described, revolve the shafts E and J, and give an inward motion to the carriage, and wind the yarn on the bobbins or spindles, at the same time the shaft E, being connected with the

carriage as above described, and the shaft J, operating the spindle by means of the usual intermediates. During this operation, in consequence of the usual connection of the twist-shaft J with the driving-shaft, for the purpose of revolving the former shaft, to give motion to the spindles to spin the yarn, the latter shaft is also partially revolved, but this is obviated by a blank in the toothed wheel f on the end of the shaft.

Having thus fully described my improvement in spinning mules, what I claim therein as new, and desire to secure by Letters Patent, is—

1. The combination of the loose pulleys 1 and 2, constructed and applied as described; with the driving-shaft C, for giving the inward motion to the carriage, and winding the yarn on the spindles, the said pulleys acting through the pulleys 3 and 3', the band F, and cord e, for giving an inward motion to the carriage, and the pulleys 4, 5, 7, 8, and 9, and bands G, I, R, and S, or their equivalents, for operating the spindles, as above set forth.

2. The combination of pulley 1 with pulley 3 by means of the cross-belt F, for operating the shaft E, substantially as described and for the purpose specified.

3. The combination of pulley 2 with pulley 5, on shaft J, by means of the intermediate double pulley 4, and belts G and I, for operating said shaft, substantially in the manner described and for the purpose specified.

4. Constructing the back-catch L with the shoulder b, and combining with said catch the vertical rod M, lever N, and rod Q, or its equivalent, the said parts being arranged for joint operation, substantially as described and for the purpose set forth.

In testimony that the above is my invention I have hereunto set my hand and affixed my seal this 5th day of July, 1866.

GEORGE GROWTHER. [L. S.]
